UNITED STATES PATENT OFFICE.

NICK MASTERS, OF WYATT, WEST VIRGINIA.

ADJUSTABLE AUGER.

1,410,206.

Specification of Letters Patent. Patented Mar. 21, 1922.

Application filed November 27, 1920. Serial No. 426,857.

To all whom it may concern:

Be it known that I, NICK MASTERS, a citizen of the United States, residing at Wyatt, in the county of Harrison and State of West Virginia, have invented certain new and useful Improvements in Adjustable Augers, of which the following is a specification.

This invention relates to new and useful improvements in adjustable augers, for boring or drilling holes, as for example boring holes in various materials, and may also be used advantageously for fence post hole drilling or boring.

The primary object of the invention is to provide a device of the above nature, which embodies an adjustably mounted bit or drill rod, which may be used for boring horizontally, vertically, or at any angle.

Another important object of the invention is to provide in combination, a bit or drill bar or rod which is adjustably mounted for operation at any angle, and means for rotating the drill bar as well as forcibly feeding the same into its work.

Other objects and advantages of the invention will become apparent during the course of the following description.

In the accompanying drawings forming a part of the application, and wherein like numerals are employed to designate like parts throughout the several views.

Figure 1 is a side elevation of the device.

Figure 2 is a transverse section through the same, taken on the line 2—2 of Figure 1, and

Figure 3 is a transverse horizontal section taken on the line 3—3 of Figure 2.

Referring to the accompanying drawings wherein for the purpose of illustration is shown the preferred embodiment of my invention, the numeral 4 designates the supporting frame in its entirety, and which consists of a base 5 having a central aperture 6 therein for a purpose which will be presently described. Rising from opposite ends of the rectangular base are standards 7 suitably supported to insure rigidness thereto.

A horizontally disposed shaft 8 has its opposite ends journaled in the standards 7, and one end of the shaft is extended beyond one standard whereby a crank or other suitable means may be applied thereto for transmitting movement to the shaft. An auxiliary drill bar supporting frame 9 consists of an arched member having its ends formed

into collars 10 through which extends the shaft 8 whereby the auxiliary frame 9 is loosely mounted thereon and capable of swinging entirely around the shaft 8, as a center. It will of course be obvious that any suitable means may be provided if desired, for retaining the auxiliary frame disposed centrally upon the shaft, and spaced from the standards 7. In its normal position, this frame hangs from or depends from the shaft 8, as clearly seen in Figure 1. An internally threaded sleeve 11 open at both ends is connected to one side of the medial portion of the arch forming a part of the auxiliary frame and is preferably formed as an integral part thereof. The sleeve adjacent its opposite end is secured to the side of a collar 12, as best seen in Figure 2, which collar is loosely mounted upon the shaft 8 equi-distant between the collars 10 forming parts of the auxiliary frame 9.

A drill bar 13 is externally screw threaded and adapted to extend longitudinally through the sleeve 11 to co-operate with the interior threads thereof. The drill bar is provided with a longitudinally extending groove 14 as best seen in Figures 2 and 3, for a purpose which will be presently described. The lower end of this drill bar extends below the lower end of the sleeve 11 and is there provided with a suitable chuck 15 for the reception of one end of a drill bit 16. A set screw 17 or other pivotal means are provided upon the chuck for detachably retaining the drill bit in engagement therewith.

The means I provide for rotating the drill bar 13, and forcibly feeding the same so that the drill bit will be forcibly fed into its work, consists of a relatively large gear 18 keyed to the shaft 8 between one collar 10 and the collar 12, and which is adapted for meshing engagement with a smaller gear 19. This smaller gear has its central opening 100 or bore equipped with an inwardly extending tongue or lug 20 adapted to ride within the longitudinally extending groove 14 of the threaded drill bar. As best seen in Figure 2, the gear 19 is disposed horizontally and has the drill bar 13 extending through its central opening or bore. As clearly seen the gear 19 is adapted for rotation between a pair of sections of the sleeve 11.

From the foregoing description it will be apparent that when the shaft 8 is rotated

the gear 18 will be similarly actuated thereby imparting rotation to the smaller gear 19 through their meshing engagement. Rotation of the smaller gear 19 will cause rotation 5 of the threaded drill bar 13, the drill bit 16, and due to the tongue 20 of the small gear extending into the groove 14 in the threaded drill bar, the latter will be caused to positively move from one end of the sleeve 10 11 to the other, according to the direction of rotation of the shaft 8. Consequently, the drill bit will be forcibly rotated and forcibly fed into its work, and when adapted for boring fence post holes, it will pass down 15 through the opening 6 in the base 5 and worm its way into the ground to consummate the formation of the post hole.

However, when the invention is adapted 20 for operation upon various materials, such as wood, metal and the like, which work is arranged, say for instance, in a vertical plane to one side of the shaft 8, it will be seen that the auxiliary frame 9 may be swung to a horizontal position to similarly 25 dispose the drill-bar 13 which will cause the relatively small gear 19 to roll around the gear 18 until the former is disposed vertically. The drill-bit 16 will then be in position to operate upon work vertically disposed and upon rotation of the shaft 8 will 30 be rotated and forcibly fed into its work.

From the construction heretofore set forth, it will be obvious that the collars 10 of the auxiliary frame may or may not be 35 provided with means for preventing the auxiliary frame from moving longitudinally of the shaft 8 so that it will be optional with the operator as to whether it is desired to permit the shaft to move in this direction or 40 not. However, when such movement of the auxiliary frame relative to the shaft 8 is desired, the relatively large gear 18 will be slidably associated with the shaft yet connected thereto in such a manner that it will 45 rotate with the shaft, so that the auxiliary frame and gear 18 may be moved from one end of the shaft to the other. Consequently,

the drill-bar 13 besides being capable of rotation about the shaft 8 as a center, may be also adjusted longitudinally of this shaft, or 50 in other words, laterally of the plane in which the drill-bar is capable of movement.

The foregoing description and accompanying drawings have reference to what might be considered to be the approved or preferred form of my invention. I desire it to be understood that I may make such changes in the construction, combination and arrangement of parts, materials, dimensions, et cetera, as may prove expedient and fall 60 within the scope of the appended claims.

Having thus fully described my invention, what I claim as new and desire to secure by Letters Patent is:—

1. An adjustable auger, comprising in 65 combination, a frame, a shaft mounted therein, an arch shaped auxiliary frame having its ends loosely connected to the shaft, an offset sleeve carried by the auxiliary frame, a drill bar mounted therein, and 70 means for rotating and forcibly feeding the drill bar.

2. An adjustable auger, comprising in 75 combination, a frame, a shaft mounted thereon, an auxiliary frame loosely mounted upon the shaft and being capable of swinging movement about the shaft as a center and slidably therealong, a drill bar carried by the frame, and means for rotating and 80 forcibly feeding the drill bar.

3. An adjustable auger comprising in combination, a frame, a horizontally disposed rotatable shaft mounted thereon, an auxiliary frame loosely mounted upon the shaft and being capable of swinging movement 85 about the shaft as a center, and a drill bar carried by the auxiliary frame and being rotated by the rotation of the shaft.

In testimony whereof I affix my signature in presence of two witnesses.

NICK MASTERS.
